PENCIL LEAD SHARPENERS

Edmund C. Pratt, Fullerton, Calif.

Application October 12, 1954, Serial No. 461,830

7 Claims. (Cl. 120—91)

This invention relates to lead pointer or pencil sharpeners used by draftsmen, architects, photo retouchers and others who employ long leads of varying degrees of hardness in mechanical pencils. However the device can be used to point the lead in the older type of wood pencil if the wood is cleared away exposing three-quarters of an inch to one inch of lead.

An object of the invention is to produce an efficient device to sharpen the lead in pencils that is rapid in operation, simple in construction and which will produce a variety of types of lead points without adjustment.

Another object is to produce a device to point the leads of a pencil in a choice of three lengths, blunt, medium and needle, but with all of these points neatly centered and true.

Another object is to provide means to remove the surplus graphite particles which adhere to the lead of a freshly-pointed pencil and which are customarily wiped off on a rag.

Another object is to provide a table of decimal equivalents or other needed data, mounted on the device so that the user can revolve the top of same to bring the chosen data to the foreground for easy reading.

Other objects and advantages of the invention will be apparent from a study of the following specification and drawings.

Although, in common with many present-day pencil sharpeners, this invention utilizes the surface of abrasive cloth or paper to make the points on the leads, the instant device employs a cylinder of abrasive rather than some cone-shape or other shaped part which must be fabricated by more expensive means. The abrasive cylinders or bands here used can be fabricated in abrasive-covered cloth or paper in long lengths or tubes and then cut to size and notched, resulting in less expensive replacement parts for the user.

Referring to the drawings, which illustrates a preferred embodiment of the invention:

Figure 1 is a perspective view of a device embodying the invention.

Figure 2 is a vertical sectional view of the device, Figure 1.

Referring to Figure 2, the numeral 10 denotes a rocker cup of metal or other suitable material loosely fitting about stud 12 so it can wobble thereon. This is urged upward by spring 11 against a land on the cylindrical stud 12.

Cup 10 has mounted thereon the abrasive sleeve 13 which is forced downwards on the cup until it engages means such as the land 14 engaging a notch in the sleeve to prevent rotation thereof. Cup 10 is prevented from rotation about the stud by pin 15 which is pressed into base 16 and extends upward through the bottom of cup 10 through an oversize hole 10a so as not to prevent the cup from wobbling or tipping in any direction when urged sidewise by the lead in a pencil inserted through holes 17 in the nozzles 18.

Numerals 19 denotes a guide washer with a slanting

2

edge fitted into the top of cup 10 to guide the blunt end of a broken lead down over the upper edge of the abrasive cylinder 13.

Spring 11 is loosely set into a circular recess 20 in base 16 and urges cup 10 upwards to the land on stud 12, but in operation, permits the rocker cup to deviate from its normal position in any direction as urged by the lead in a pencil inserted through any of the nozzles 18.

The numeral 21 denotes a revolving cap into which 10 is cast or pressed three or more nozzles, such as 18, which are spaced in a circle on the top of cap 21, but at different distances from the center thereof. These nozzles are mounted or cast into the top of cap 21 at different angles, so that when a pencil is inserted into any one of them with the lead extended to go through a hole 17, the angle at which the lead engages abrasive cylinder 13 is different by a few degrees from what it would be in any other nozzle. This causes the pencil lead to rock the rocker cup 10 degrees more or less from its normal position.

It is the combination of the two angles which thus produces on the extended lead of the pencil various lengths of points, and which is an important feature of the invention and enables different points to be produced 25 without adjustment of the device.

By reference to Figure 2, it will be seen how the angle of the nozzle 18 on the right and its less distance from the center of cap 21 causes, when a lead is inserted through hole 17 therein, the rocker cup 10 to tip more and produce a greater angle with the lead and thus produce a shorter, more blunt point than when the same pencil and lead are inserted through the left nozzle.

Cap 21 revolves on a bearing 22 formed by stud 12, which is pressed into base 16, and is also threaded at its upper end at 23 to receive the similarly threaded bottom of pot 24.

The pot 24 is used for two purposes: first it acts as a retainer nut to hold cap 21 in position so it can revolve about stud 12, secondly pot 24 forms a container for the nest of chain woven plastic 25 or some other suitable material used to clean the loose graphite particles off a freshly sharpened lead.

Such chain woven plastic is in common use and is made from several plastic materials such as polyethylene. 45 Here it is put to a new use for which it has not been previously employed. The chain is composed of small links of rectangular material so that the links have sharp edges which engage and remove the loose graphite particles.

The plastic nest 25 is retained by top 26 which has a hole 27 in its center of sufficient size to permit the user to insert the lead of a freshly sharpened lead into it to clean its surface before using it to draw with.

On the skirt of cap 21 is mounted a band of paper, metal foil or other material bearing a printed chart containing data useful to the user, such as decimal equivalents. This chart band 28 can be revolved by the user until the section of the chart bearing the particular data desired is in front where it may easily be seen and read.

Base 16 is preferably cast in iron or die-cast in zinc or brass so it will be fairly heavy and the bottom of it should be covered with skid-proof rubber 30 so that in operation the user will not be forced or tempted to hold the device with one hand while rotating the cap 21 with his pencil.

The cylindrical apertures in nozzles 18 are drilled or cast of an internal diameter just sufficient to hold any of many types of mechanical pencils or lead pencils, while the holes 17 are drilled or cast a few thousandths larger in diameter than the usual leads sold to architects, draftsmen and photo retouchers and others, which leads vary in diameter plus or minus four thousandths from a mean

of .075. Experimenting has proved that the sizes of the holes in nozzles 18 and holes 17 are not too critical.

It is almost impossible to break a lead while sharpening a pencil in the device just described, as the user cannot exert enough sideways pressure to offset the resilience of the rocker cup 10 on its spring 11. In practical use, the user may as often insert a partially sharpened lead, the point of which has slightly worn dull by use in drawing or retouching, as inserting a blunted broken lead with no point as yet on it at all. In either event the pressure of the lead as it is guided over guide washer 19 to contact the abrasive cylinder 13 can not only tip the rocker cup 10 from its normally centered position as urged by spring 11, but the entire assembly of rocker cup 10, guide washer 19 and abrasive cylinder 13 can give away downwards upon the urging of the lead in the pencil, yet exert enough gentle pressure on the lead to sharpen it to a true-centered point in a few revolutions of cap 21.

In use, the device is placed upon a table or drafting board or other surface, the pencil or mechanical pencil holder with its lead protruding about three-quarters of an inch is inserted in the chosen nozzle 18 (depending upon the length point desired), and, holding the pencil between the fingers, the cap 21 of the device is revolved several times, either clockwise or counter-clockwise until, by removing the pencil and examining it, the conical point is finished to the satisfaction of the user. It is possible, by this method to satisfy those who want an almost sharpened point but who prefer not to have the point a needle-like tip.

All particles of graphite which are ground off on the abrasive sleeve 13 drop into the recess 29 in the base 16 where they accumulate; and the device is operable even after the recess is more than half full of accumulated powdered graphite.

When the surface of the abrasive sleeve 13 has become worn to the point where too many revolutions of cap 21 are required to produce a sharp point quickly, it is only necessary to unscrew the pot 24 to release revolving cap 21, reach in and remove the guide washer 19 and take off the worn out sleeve, replacing it with a new one.

The chain-woven mesh of plastic 25 which the user utilizes to take off the smudge-making graphite particles from his newly-sharpened lead, permits the particles to drop to the bottom of pot 24 because of the slick surface of the plastic. Thus many months of graphite dust accumulation in the pot do not prevent continued use of the plastic 25, the top layer of which will function for a long time.

It is to be understood that the above description of the invention is merely illustrative and not limitative, as many changes can be made therein, the invention being as defined by the appended claims.

It will also be noted that the sleeves 13 are salable as a replacement part separately from the unit device and are therefore claimed as a separate invention for use in devices of the class described.

The complete cup 10 with sleeve 13 and guide washer 19 is also salable separately as a replacement part and is so claimed as well as the chain woven plastic 25 which comprises a new method of removing the loose graphite particles when employed in a device of the character described and may be used for the described purpose in any suitable holder with other types of sharpeners.

What is claimed is:

1. A pencil lead pointer including a base having an upstanding annular flange; a stud mounted in said base and extending upwardly above said flange and having spaced shoulders formed thereon, one facing upwardly and substantially 90° with respect to the axis of the stud and the other facing downwardly and having its surface inclined relative to said axis; a rocker cup supported on said stud in a non-rotative state, yet free to wobble thereabout; spring means urging an opening in the base of said cup

against said shoulder; abrasive material carried by said cup; a revolvable cap mounted on said stud and having a skirt portion extending downwardly and overlying said flange on said base; and a plurality of sockets carried by said cap, each having a bore spaced at a different radial distance from the axis of said cap, and each of said bores being at a different angle to the normal axis of said cup and at a different angle from any other bore.

2. In a pencil lead pointer, a base having a circular cavity therein, a stud mounted in said base and having its axis coinciding with the axis of said cavity, a first shoulder formed on said stud disposed substantially 90° relative to the axis of said stud and facing upwardly, a second shoulder formed on said stud and inclined to the axis thereof and facing downwardly, a cup embracing said stud and bearing against said second shoulder and consequently having its axis eccentric to said first mentioned axes, spring means urging said cup upwardly against said second shoulder, means keying said cup against rotation, an abradant carried on the outer surface of said cup, said spring means comprising a comparatively light spring acting against said cup and causing it to tend to resist angular displacement, a cap forming a closure for said cavity and having a hub journaled on said stud, a socket formed in said cap to accommodate a pencil lead holder, said socket having its axis so related to the axis of said stud that a pencil lead carried by said holder angularly displaces said cup and is pointed at a predetermined angle as said cap is rotated.

3. In a pencil lead pointer, a base having a circular cavity therein, a stud mounted in said base and having its axis coinciding with the axis of said cavity, said stud having upper and lower shaft portions with an intermediate portion of larger diameter for providing opposed shoulders, one facing upwardly and one facing downwardly, a cup embracing said stud and having a closure wall with a hole therein bearing on the lower of said shaft portions, spring means between said wall and the bottom of said cavity urging said wall into contact with said last shoulder, means keying said cup against rotation, an abradant carried on the outer surface of said cup, said spring means acting against said cup and causing it to tend to resist angular displacement, a cap forming a closure for said cavity and having a hub journaled on the upper shaft portion of said stud, and a socket formed in said cap to accommodate a pencil lead holder, said socket having its axis inclined relative to the axis of said stud so that a sharp point is formed on a pencil lead carried by said holder as said cap is rotated.

4. In a pencil lead pointer, a base having a circular cavity therein, a vertical stud rigidly carried in said base, said stud having upper and lower shaft portions with shoulder means therebetween, said means having upwardly and downwardly facing shoulders and said downwardly facing shoulder having its face inclined at an angle greater than 90° relative to the axis of said stud, a cup embracing said stud and having a wall portion with a hole therein bearing on said lower shaft portion, means in said base keying said cup against rotation, an abradant carried on the outer surface of said cup, a comparatively light spring acting upwardly against said cup, holding the wall portion thereof against said downwardly facing shoulder and causing said cup to tend to resist angular displacement, a cap forming a closure for said cavity and having a hub journaled on said upper shaft portion and bearing against said upwardly facing shoulder, a plurality of sockets formed in said cap to accommodate pencil lead holders, said sockets having their axes forming different angles with the axis of said stud, so that a pencil lead carried by said holder positioned in any one of said sockets displaces said cup and is pointed at a different angle thereby, than is produced with the holder in either of the other sockets, as said cap is rotated.

5. In a pencil lead pointer, a base having a circular

well formed therein, a vertical stud in said well and rigidly mounted in said base, said stud having upper and lower shaft portions with upwardly and downwardly facing shoulders therebetween, the second shoulder being adjacent to the lower shaft portion having its surface inclined at an angle of less than 90° with respect to the axis of said stud, a cup embracing said stud and having a bottom wall with a hole therein bearing on said lower shaft portion, spring means urging said bottom wall against said last mentioned shoulder, means keying said cup against rotation, an abradant carried on the outer surface of said cup, a cap forming a closure for said cavity and having a hub journaled on said stud with its lower end in contact with said upwardly facing shoulder, a plurality of sockets formed in said cap each adapted to accommodate a pencil lead holder, said sockets having their axes forming different angles relative to the axis of said stud so that a pencil lead carried by said holder positioned in either of said sockets may be selectively pointed sharp, medium, or blunt as said cap is rotated.

6. In a pencil lead pointer, a base having a circular well formed therein, a vertical stud in said well and rigidly mounted in said base, said stud having upper and lower shaft portions with upwardly and downwardly facing shoulders therebetween, the shoulder adjacent to the lower shaft portion having its surface disposed at an angle of less than 90° with respect to the axis of said stud, a cup embracing said stud and having a bottom wall with a hole therein bearing on said lower shaft portion, spring means urging said bottom wall against said last mentioned shoulder, means keying said cup against rotation, an abradant carried on the outer surface of said cup, a cap forming a closure for said cavity and having a hub journaled on said stud and having its lower end in contact with said upwardly facing shoulder, a plurality of sockets formed in said cap each adapted to accommodate a pencil lead holder, said sockets having their bases different radial distances out from the axis of said stud and angularly disposed so that a pencil lead car-

ried by said holder may be positioned in either socket in accordance with whether a sharp point, a medium point, or a blunt point is desired, and the selected point is obtained when said cap is rotated.

5 7. A pencil pointer including a base, a stud mounted in said base and having a 90° shoulder thereon facing upwardly and having an inclined shoulder facing downwardly, a tiltable rocker cup supported on said stud and normally inclined due to contact with said inclined shoulder, spring means extending between said base and said cup and urging the cup upwardly against said inclined shoulder, keying means extending between said cup and said base to prevent the cup from rotating on said stud while permitting said cup to wobble about the axis of said stud, abrasive means carried on the external periphery of said cup and overlying the outer surface thereof, and a revolvable cap mounted on said stud above said 90° shoulder, said cap having a plurality of pencil receiving openings therein having their axes angular with respect to the axis of said stud with such angle in each case being different from the others, each of said openings being adapted to receive a pencil and guide the lead thereof into engagement with said abrasive means at a particular angle thereto which is different from the angle occasioned by any other opening.
